UNITED STATES PATENT OFFICE.

HJALMAR G. CARLSON, OF WORCESTER, MASSACHUSETTS, ASSIGNOR TO ROCKWOOD SPRINKLER COMPANY OF MASSACHUSETTS, OF WORCESTER, MASSACHUSETTS, A CORPORATION OF MASSACHUSETTS.

CONSTANT-ALARM DEVICE FOR ALARM VALVES.

Application filed February 4, 1926. Serial No. 86,072.

When water spurts from an opened sprinkler on an automatic sprinkler system it is important to have a continuous alarm sounded. The usual means provided consists of three elements: a check valve in the main riser pipe, having a grooved or annular seat, an automatic drip-chamber connected by pipes to both the groove and to an alarm means such as a water motor or electric circuit closer operating a gong. The drip chamber has a valve-controlled waste outlet for wasting part of the water as it enters, to slow down the rate of filling it completely. The purpose of the drip chamber is to prevent the gong from being rung by a "water hammer". "Water hammer" is the popular name given to the sudden rise in pressure which occurs whenever the rate of flow of water in a supply system is suddenly reduced. Such an increase of pressure will cause the check valve to lift and admit water to both the system and the drip chamber.

It has been found in practice that the time of duration of a water hammer is quite variable and depends both upon its force and upon the amount of air trapped in the extremities of the sprinkler pipes. The more such air there is, the longer time it takes a given rate of flow of water up the riser to cease its upward motion and start back again under the influences of gravity and the compressed air. The return wave of flowing water re-seats the valve, thus cutting off the supply of water to the drip chamber. So desirable is it to prevent water hammers from causing the alarm to ring that it has been the custom to provide capacity enough in the drip chamber to prevent the water from completely filling it even under the most adverse conditions produced by such hammers.

While, however, a sufficiently large drip chamber will solve the foregoing problem, it introduces a new trouble for such increase in size is in part itself the cause of discontinuous ringing of the gong when the upward flow of water by the check valve is

due, not to water hammer, but to an open sprinkler. Indeed it may cause entire failure of the gong to ring because of the suction on the back of the check valve induced by the flow of water through the groove when the valve has opened just enough to supply one or two open sprinklers. When a sprinkler opens the first rush of water therefrom is not caused by the outside water supply pressure, but by the air bottled up in the extremities of the sprinkler lines. This air pressure must fall a few pounds per square inch before the water supply pressure can overcome the differential load on the two sides of the check valve, caused by the presence on its under side. The consequence is that when release takes place the valve bounds open clear to its extreme position and remains there until the motion of the water by it is arrested by the rising air pressure and a return wave or flow takes place. Then the valve may be slapped back to its seat again before the drip chamber has been entirely filled and an alarm sounded; or this action may be sufficiently sluggish to occupy more than enough time to fill the drip chamber and ring the gong, only to then occur and stop the water supply to drip chamber and gong, thereby stopping the alarm. It was to correct this action that the device shown in Patent Number 1,051,266, patented January 21, 1913, was invented by George I. Rockwood. In that invention a small auxiliary check valve, having a capacity for supplying two or three sprinkler heads, was piped around the main check valve, the purpose being to prevent most of the above described return wave of the water after the small check valve has opened. This was effected by so throttling the water supply through the auxilliary check valve that the purely inertia effects of the stream of water in the riser were reduced to a minimum.

Experience has shown, however, that in certain circumstances there may be very much the same intermittent ringing or absence of ringing as when only the large

main check valve is used. The small valve diminishes but does not do away entirely with the difficulties described.

The principal object of my invention is to provide automatic and positively operating means for controlling the reseating of the auxiliary check valve of the Rockwood type of alarm check valve during the period of existence of such return wave as there is when the auxiliary check valve opens in response to the flow from an opened sprinkler.

Other objects and advantages of the invention will appear hereinafter.

Reference is to be had to the accompanying drawings, in which

Fig. 1 is a central sectional view of an alarm valve of the Rockwood type with a preferred embodiment of this invention applied thereto; in the position wherein the alarm valve has just been closed by a water hammer and the auxiliary valve is just beginning to close.

Fig. 2 is an elevation of one side of the same;

Fig. 3 is a sectional view on the line 3—3 of Fig. 4; and

Fig. 4 is an enlarged view of part of Fig. 1.

I have shown this invention as applied to a well known type of alarm valve device comprising the casing 9 and the valve, which consists of two plates 10 and 11. The valve rests on a circular valve seat 12. The area of the valve on the under side, which is exposed to the main water pressure, is less by the area of the seat than the area of the valve on the upper side, which is subjected to substantially the same pressure above. In other words, it is a differential valve which will remain closed if the pressure on both sides is the same. This valve is pivoted at 13. The valve seat 12 is provided with a groove 14 which, in this case, as usual, is connected by a pipe 25 with an alarm bell 26 and adapted to operate the same when the valve opens and this groove is exposed to the pressure of the water in the system. This construction, although commonly used, is open to the objection above specified and is also affected by the fact that the current of water rushes by this groove at a high velocity, thus at times relieving it of some of the pressure.

A by-pass 15 is provided allowing the water from the system constantly to enter a chamber 16 outside the valve chamber so that this chamber will remain under the pressure of the water in the main. This chamber has an opening into the interior of the valve casing which is provided with another differential valve 17 having a higher ratio of difference between the two areas than is the case with the valve 11, as shown in Fig. 1. Therefore the valve 17 will open

under a lesser reduction of pressure above and if only one or two sprinkler heads are open this valve 17 will open and allow the water to pass by into the sprinkler system even when the valve 11 is closed. All this is shown in the said Rockwood patent.

The valve 17, besides closing the chamber 16, also closes the end of a tube 19 connected with a pipe 20 which is connected with the alarm pipe 25 to which the water from the groove 14 flows. Therefore the alarm will be operated by either or both. The valve 17 is pivoted at 21 on a lever 23. An adjustable limit bolt 22 is provided for limiting the amount of its motion inwardly about its pivot. This arrangement minimizes the difficulties above specified but does not entirely eliminate them if only the parts that have been so far described are employed. It will be understood of course that when the valve 11 opens, the pressure on the valve 17 will close it and the operation of the alarm will be provided for only from the groove 14.

For the purpose of preventing the sudden closing of the valve 17 and thus allowing the water to flow through the pipe 20 for a longer period of time so as to cause the alarm to operate continuously. I provide a flexible diaphragm 30 in a chamber 31 at the side of the valve casing. The water is admitted to the inner side of the diaphragm by a passage 36. Secured to this diaphragm is a tube 32 extending through the passage 36 and pivoted at 33 to the lever 23. At the outer end of this tube is a seat preferably conical in form and having a leak passage 33^a of small area through which water can pass at all times. Back of this seat is a ball 34 adapted to close the seat except for the small by-pass. There is a cover or cap behind the ball to keep it from getting out of position but having a slot 35 adapted to permit the flow of water. On account of these conditions it will be understood that the chamber 31 on both sides of the diaphragm 30 is constantly full of water under pressure and that the diaphragm will move one way or the other according to changes in the pressure of the water.

In operation, as described above, when the check valve 11 is released it bounds wide open and remains there until the flow of water by it is stopped by the rising air pressure and a return wave is exacted. The valve 11 is liable to be slapped back to its seat before the drip chamber 16 has been filled and the alarm sounded, or late enough to stop the alarm after it has started. The force required to open the auxiliary check valve will overcome any resistance in the chamber 31 because water can flow into it and out of it freely on both sides of the diaphragm when there is no pressure to close the valve 34. Therefore the valve 17 will open easily due to pressure in the passages

15 and 16 and the lever 23 may swing out to its limiting position, thus flexing the diaphragm inwardly toward the valve casing. Now in case of a water hammer caused as above described a sudden pressure exerted would tend to close the valve 17 quickly and thus cause the trouble I have referred to. But on account of the resistance which is caused by the attempt to force the tube 32 inwardly, the valve 34 will be closed by the attempt of the water on the outer side of the diaphragm to rush through the tube 32. The pressure of the water back of the valve 34 will force it to its seat. Then only a very small quantity of water will flow out of the chamber 31 through the passages 33^a and 32 and the valve 17 cannot close instantly. In fact, it will take considerable time for it to close, generally longer than the water hammer lasts. This keeps communication open from the main valve chamber to the pipe 20 and causes the alarm to be sounded continuously and without intermission. If the back pressure continues long enough the valve 17 will be caused to close slowly. After the valve 11 opens, the water will be allowed to rush into the valve chamber with such rapidity that the pressure will be removed from the rear of the valve 17 and that will close as rapidly as the valve 34 will permit.

It will be seen therefore that by this simple arrangement the intermittent operation of the alarm will be converted into a constant one and the alarm will operate constantly without intermission until conditions become stabilized.

Although I have illustrated and described only a single form of the invention I am aware of the fact that modifications can be made therein by any person skilled in the art without departing from the scope of the invention as expressed in the claims.

Therefore I do not wish to be limited to all the details herein disclosed but what I do claim is:—

1. The combination with an alarm valve, of an alarm, means for conducting water from said valve to said alarm, a second means for conducting water to the alarm, a second valve for closing the connection of said second means to the alarm, and means for retarding the closing of the second valve.

2. The combination with an alarm valve, of a by-pass from the main thereof, an alarm, means leading from the seat of the main valve to operate said alarm, means leading from the by-pass to operate said alarm, a differential valve for closing the connection of the by-pass to said alarm, the second valve being constructed and arranged to open under a lesser difference in pressure than the main valve of the system, and means for retarding the closing of the second valve.

3. The combination with an alarm valve

and an alarm, of a by-pass from the high pressure side of the main valve, a chamber connected with said by-pass, a tube in said chamber, means for connecting said tube to the alarm, said chamber opening into the main valve chamber, a differential valve for closing said opening and closing the end of said tube, a lever connected with the second valve, means for limiting the swing of said lever and therefore the opening of the valve, and means for preventing the lever from moving back rapidly to seat the valve after the valve is once opened.

4. The combination with an alarm valve having a groove in the valve seat connected with an alarm, of a by-pass from the high pressure side of the main valve, a chamber connected with said by-pass, a tube in said chamber, means for connecting said tube to the alarm, said chamber opening into the main valve chamber, a differential valve for closing said opening and closing the end of said tube, the last named valve having an area exposed to the water pressure in the main valve chamber materially larger than the area exposed to the pressure in the by-pass chamber, the proportion being such that the second valve will open before the main valve in case of the lowering of the pressure in the valve casing, a lever connected with said valve, means for limiting the swing of said lever and therefore the opening of the valve, and means for preventing the lever from moving back rapidly to seat the valve after the valve is once opened.

5. The combination with an alarm valve casing and valve, of a by-pass connected thereto, a chamber connected with the by-pass and having an opening into the interior of said valve casing, a tube in said chamber connected to conduct water to an alarm device, a valve for closing said opening, said tube being in position for its end to be closed by the valve when in closed position, a second chamber in open communication with the interior of the valve casing, a diaphragm across the second chamber, a tube connected with said diaphragm and connected with said valve, said tube being open to the interior of said casing to admit water into the second chamber behind the diaphragm, and a movable valve in the tube adapted to be closed by the pressure of water from the chamber behind the diaphragm toward the valve casing to slow down the closing of the second valve.

6. The combination with an alarm valve casing and valve, of a by-pass adjacent thereto, opening into the interior of said valve casing, a tube connected to conduct water to an alarm device, a valve for closing said opening, said tube being in position for its end to be closed by the valve when in closed position, a second chamber in open communication with the interior of the valve

casing, a diaphragm across the second chamber, a tube connected with said diaphragm and connected with said valve for restricting the closing of the valve after it is opened, said tube being open to admit water into the second chamber behind the diaphragm from the valve casing and having a valve

seat provided with a leak passage, and a movable valve in the tube to be closed by the pressure of water behind it in the chamber.

In testimony whereof I have hereunto affixed my signature.

HJALMAR G. CARLSON.
